UNITED STATES PATENT OFFICE.

ROLAND O. CRAIG, OF ORCUTT, CALIFORNIA, ASSIGNOR TO HENRIETTA CRAIG, OF LOS ANGELES, CALIFORNIA.

SAND-REEL DRIVE FOR WELL-DRILLING EQUIPMENT.

Application filed September 7, 1922. Serial No. 586,662.

To all whom it may concern:

Be it known that I, ROLAND O. CRAIG, a citizen of the United States, residing at Orcutt, in the county of Santa Barbara and 5 State of California, have invented a new and useful Sand-Reel Drive for Well-Drilling Equipment, of which the following is a specification.

My invention relates to hoisting devices 10 which are employed in the drilling of wells and which are particularly employed in oil well drilling.

In the present form of equipment a sand reel is provided on which is wound a light 15 cable for the purpose of hoisting articles such as sand bailers. This sand reel is mounted on a shaft together with a friction wheel and is driven by the contact of this friction wheel with the periphery of the 20 band wheel. Band wheels, owing to the fact that they must be of considerable diameter are constructed of wood, and are therefore of an inflammable nature which makes them liable to catch fire or smoke under the 25 action of the friction of the sand reel friction wheel thereagainst. This action of the friction wheel against the band wheel serves to greatly reduce the life thereof owing to the severe wear incurred by the friction between the two members; furthermore, the 30 friction wheel operates against the belt receiving surface of the rim of the band wheel and deleteriously affects it to such an extent that the belting is injured by the splinters and abrasions which are present 35 on the periphery of the band wheel, thus reducing the wearing life of the belt.

It is an object of my invention to provide an improved drive for sand reels, and 40 other hoisting devices of a similar nature, which may be mounted upon the band wheel shaft and operated through the engagement of cooperating clutch elements which are secured upon the drive sprocket and the 45 band wheel shaft.

It is a further object of my invention to provide an improved form of sprocket having associated therewith a clutch member and a brake member which may be integrally formed with the drive sprocket.

The specific advantages of my invention and further objects thereof will be made evident hereinafter.

Referring to the drawing which is for illustrative purposes only,

Fig. 1 is a plan view showing a well-drilling rig equipped with a sand wheel embodying the principles of my invention.

Fig. 2 is a fragmentary elevation of the band wheel shaft with the sand wheel drive 60 clutch mounted thereupon, taken as indicated by the line 2-2 of Fig. 1, a portion of the drive sprocket being shown in section therein.

Fig. 3 is a fragmentary plan view of a 65 modified form of my invention showing a preferred form of practicing the invention. In this view I illustrate the use of my simplified form of drive sprocket having associated therewith a drive clutch and a brake 70 clutch of simple design.

Fig. 4 is an elevational view of a modified form of my invention showing the manner in which the operating yoke which I employ with my improved form of sprocket wheel 75 is manipulated by a screw having a small sprocket mounted thereupon.

In Fig. 1 of the drawing I show a derrick 11 having a platform 12, a bull wheel 14, and a calf wheel 15; all situated in accordance 80 with standard practice. Upon a framework 16 of sills 17, a band wheel 19 is supported upon a band wheel shaft 20, which is journaled in bearing boxes 22, mounted upon the upper end of jack posts 23. Upon the 85 band wheel shaft 20 a sheave 25 serving as a tug wheel is turnably mounted, and is adapted to be driven from the shaft 20 by means of a clutch 26 splined upon the shaft 20 and adapted to be moved axially thereupon by means of a yoke 27 operated from a lever 28 mounted upon the platform 12 by means of a rod 29. The shaft 20 has also 90 turnably mounted thereupon a calf wheel drive sprocket 32 over which a chain 33 extends to the calf wheel 15. This drive sprocket 32 is also driven from the shaft 20 by the engagement of the clutch 26, therewith, such construction being the subject of a companion application for patent, Serial 100 No. 586,661.

Instead of employing the customary friction wheel for driving the sand wheel 35, a sprocket 36, hereinafter termed the driven sprocket, is keyed upon the sand reel 105 shaft 37. Upon the band wheel shaft 20

in alignment with the driven sprocket 36 a sand reel drive sprocket 39 is turnably mounted.

As shown in Fig. 2 the drive sprocket 39 is provided with a cylindrical extension 40 and a cylindrical extension 41. The extension 40 is recessed at 42 and receives the friction elements 43 of an expanding clutch 44 which is keyed upon the shaft 20. The clutch 44 is provided with an expander sleeve 45 through which the expansion of the friction elements 43 is accomplished by moving it upon the shaft 20 in the direction toward the drive sprocket 39, so that the toggle links 46 connected therewith are thrown into the position causing the expansion of the elements 43. The expander sleeve 45 may be thrown in and out of engagement by means of a yoke 48 which is operated by means of a rod 49 extending to a lever 50 mounted upon the platform 12 at the convenience of the driller.

The extension 41 of the sprocket 39 provides a cylindrical external face 53 around which a brake band 54 is placed, this brake band being constrictable so as to form frictional contact with the surface 53, by means of a toggle lever 55 having a pull rod 57 extending therefrom to an operating lever 58 which is also mounted upon the platform 12. By means of this arrangement a positive drive for the sand reel is provided, and also a positive braking means having a large brake surface so that the wear thereof will be distributed over a large area, thus contributing to the wearing capacity thereof.

In the preferred form of my device, as shown in Figs. 3 and 4, a drive sprocket 60 is mounted upon the band wheel shaft in the same position in which the sprocket 39 is shown in the previous figures. The drive sprocket 60 is provided with cylindrical concentric projections 61 and 62, each having a conical recess 63 and 64 adapted to engagement with members 66 and 67. The member 67 is mounted upon the intermediate supporting jack post 68 and is, in consequence thereof, stationary. The member 66 is rigidly fastened upon the band wheel shaft 20 so as to be revolved thereby. The drive sprocket 60 is adapted to separately engage either the drive member 66 or the stationary or brake member 67, by moving it laterally upon the shaft so that the desired engagement of the conical formations is accomplished. This movement of the member 60 upon the shaft is accomplished by means of a yoke member 70 which is pivoted at 71 to a base 72 having a vertical supporting arm 73 in which a block 75 receiving the rear end 76 of a screw 77 is mounted. This screw threads into a block 79 sustained by the yoke 70 and provides a means for swinging the yoke, either to the right or to the left, by the desired rotation of the screw 77, which is ac-

complished by means of a sprocket 82 mounted thereupon having a chain extending thereover to a similar sprocket mounted at the derrick platform.

The yoke 70 is provided with rollers 85 which engage an annular channel 86 in the extension 61 of the drive sprocket 60. By the comparatively fine adjustability of the position of the yoke 70 through the medium of the screw 77, it is possible to hold the drive sprocket 60 at a position intermediate between the members 66 and 67 or to bring it into forcible contact with either of these members. As shown in Fig. 3, the driven sprocket 88 is splined upon the sand reel shaft 89 and is adapted to axial movement between a pair of collars 90 and 91, so that the driven sprocket may adjust itself to alignment with the drive sprocket 60 as the drive sprocket is alternated between the driven and braked positions. This preferred form of my invention will be seen to be of an effectual, yet simple nature and may, therefore, be cheaply constructed and installed.

I claim as my invention:

1. In a sand reel drive for well drilling equipment, the combination of: a sand reel shaft; a sprocket secured upon said shaft; a band wheel shaft; a band wheel upon said band wheel shaft through which said shaft may be rotated; a drive sprocket upon said band wheel shaft; a chain running over said sprockets, cooperating clutch elements upon said drive sprocket and upon said band wheel shaft; means for engaging said clutch elements; a cylinder formed concentrically upon said drive sprocket; and a brake band adapted to frictionally engage said cylinder.

2. In a sand reel drive for well drilling equipment, the combination of: a sand reel shaft; a sprocket secured upon said shaft; a band wheel shaft; a band wheel upon said band wheel shaft through which said shaft may be rotated; a drive sprocket upon said band wheel shaft; a chain running over said sprockets, cooperating clutch elements upon said drive sprocket and upon said band wheel shaft; means for engaging said clutch elements; a stationary member; cooperating brake elements upon said drive clutch and upon said stationary member; and means for bringing said brake elements into functioning relationship.

3. In a sand reel drive for well drilling equipment, the combination of: a sand reel shaft; a sprocket secured upon said shaft; a band wheel shaft; a band wheel upon said band wheel shaft through which said shaft may be rotated; a drive sprocket upon said band wheel shaft; a chain running over said sprockets, cooperating clutch elements upon one side of said drive sprocket and upon said band wheel shaft; means for engaging said clutch elements; a cylinder

formed concentrically upon said drive sprocket, said cylinder being formed upon the opposite side of said drive sprocket from said clutch elements; and a brake band 5 adapted to frictionally engage said cylinder.

4. In a sand reel drive for well drilling equipment, the combination of: a sand reel shaft; a sprocket secured upon said shaft; a band wheel shaft; a band wheel upon said 10 band wheel shaft through which said shaft may be rotated; a drive sprocket upon said band wheel shaft; a chain running over said sprockets, cooperating clutch elements upon one side of said drive sprocket and upon 15 said band wheel shaft; means for engaging said clutch elements; a stationary member; cooperating brake elements upon said drive clutch and upon said stationary member, said brake elements being situated upon the 20 side of said drive sprocket opposite to said clutch elements; and means for bringing said brake elements into functioning relationship.

5. In a sand reel drive for well drilling equipment, the combination of: a sand reel shaft; a sprocket secured upon said shaft; a band wheel shaft; a band wheel upon said band wheel shaft through which said shaft may be rotated; a drive sprocket upon said 25 band wheel shaft, said drive sprocket having a clutch element upon one face thereof and a brake element upon the opposite face thereof; a chain running over said sprockets; a clutch element upon said band wheel shaft adapted to cooperate with said clutch element of said drive sprocket; a stationary 30 brake element adapted to cooperate with said brake element of said drive sprocket; and means for bringing said cooperating elements into functioning relationship.

6. In a drive for well drilling equipment, the combination of: a drive shaft and a driven shaft; a driven sprocket upon said driven shaft; a drive sprocket turnably 35 mounted upon said drive shaft, said drive sprocket having a clutch element upon one face thereof and a brake element upon the 40

opposite face thereof; a chain running over said sprockets; a clutch element upon said drive shaft adapted to cooperate with said 50 clutch element of said drive sprocket; a stationary brake element adapted to cooperate with said brake element of said drive sprocket; and means for bringing said co-operating elements into functioning relationship. 55

7. In a drive for well drilling equipment, the combination of: a drive shaft and a driven shaft; a driven sprocket on said driven shaft; a drive sprocket turnably 60 mounted upon said drive shaft; clutch elements upon each side of said drive sprocket; a stationary cooperating clutch element adjacent to one of said clutch elements of said drive sprocket; a cooperating clutch element 65 mounted upon said drive shaft adjacent to the other of said clutch elements of said drive sprocket; and means for moving said drive sprocket axially upon said drive shaft into engagement with either of said cooperating clutch elements. 70

8. In a drive for well drilling equipment, the combination of: a drive shaft and a driven shaft; a driven sprocket on said driven shaft, said driven sprocket being 75 splined upon said shaft so that axial movement thereof upon said shaft is provided; a drive sprocket turnably mounted upon said drive shaft; clutch elements upon each side 80 of said drive sprocket; a stationary cooperating clutch element adjacent to one of said clutch elements of said drive sprocket; a cooperating clutch element mounted upon said drive shaft adjacent to the other of 85 said clutch elements of said drive sprocket; and means for moving said drive sprocket axially upon said drive shaft into engagement with either of said cooperating clutch elements.

In testimony whereof, I have hereunto set 90 my hand at Orcutt, California, this 15 day of August 1922.

ROLAND O. CRAIG.
